SWITCHING MECHANISM

Charles W. Hawthorne and George P. Malm,
Worcester, Mass., assignors to Morgan Construction Company, Worcester, Mass., a corporation of Massachusetts

Application July 14, 1942, Serial No. 450,870

3 Claims. (Cl. 193—39)

This invention relates to switching mechanism by which elongated metal bars and the like can be directed selectively into any one of a plurality of paths, and in particular the invention is an improvement over the mechanism disclosed in the patent to Hawthorne No. 2,181,401.

The switching mechanism of the said prior patent comprises a guide device which can be moved into registration selectively with a plurality of stock receiving channels having their entrances in a horizontal row. To move the guide device from one entrance to another, it is first lowered to a path offset from the said row, then moved along this path, and finally raised to bring it into registration with the desired entrance. The movements of the guide device along the offset path are brought about by a group of hydraulic motors which are connected to the device by a series of links, levers, etc., and the vertical movements of the device are effected by an additional hydraulic motor. This requires an expensive, complicated and bulky apparatus. Furthermore, the motors are all of the single acting type and therefore provide for positive movement in one direction only, the return movement being by the action of gravity alone. This may be insufficient in some cases, particularly if some part of the mechanism should create excessive friction or resistance because of warpage, entrance of scale from the stock, lack of lubrication, or otherwise. A still further disadvantage of the prior mechanism is the necessity for additional motors when additional entrances are provided.

It is accordingly one object of the invention to provide a switching mechanism which will be of comparatively simple, inexpensive, and compact construction.

It is a further object of the invention to provide a switching mechanism which will require only two hydraulic motors.

It is a further object of the invention to provide a switching mechanism including a guide device which can be positively moved in all necessary directions.

It is a further object of the invention to provide a switching mechanism including a guide device which can be moved into registration selectively with a plurality of entrances arranged in a row, the construction being such that the movements of the device along the row can be effected by a single motor regardless of the number of entrances provided.

With these and other objects in view, as will be apparent to those skilled in the art, the invention resides in the combination of parts set forth in

the specification and covered by the claims appended hereto.

Referring to the drawings illustrating one embodiment of the invention and in which like reference numerals indicate like parts,

Fig. 1 is a plan view of a switching mechanism, with certain valves and piping omitted for clearness of illustration;

Fig. 2 is an elevation taken on the line 2—2 of Fig. 1;

Fig. 3 is an elevation taken on the line 3—3 of Fig. 1;

Fig. 4 is a plan view of an elevating motor, with certain portions shown in section;

Fig. 5 is a section on the line 5—5 of Fig. 4;

Fig. 6 is a section on the line 6—6 of Fig. 4;

Fig. 7 is a plan view of a traversing motor, with certain parts shown in section;

Fig. 8 is a section on the line 8—8 of Fig. 7;

Fig. 9 is a section on the line 9—9 of Fig. 7;

Fig. 10 is an enlarged section on the line 10—10 of Fig. 7, showing the construction of a pilot valve mechanism;

Fig. 11 is a section on the line 11—11 of Fig. 10;

Fig. 12 is a section on the line 12—12 of Fig. 10;

Fig. 13 is a section on the line 13—13 of Fig. 10;

Fig. 14 is a section on the line 14—14 of Fig. 10;

Fig. 15 is a plan view of a sleeve forming part of the valve mechanism shown in Fig. 10;

Fig. 16 is a side elevation of the sleeve shown in Fig. 15;

Fig. 17 is a section on the line 17—17 of Fig. 16;

Fig. 18 is an elevation of a control valve mechanism;

Fig. 19 is a section on the line 19—19 of Fig. 18; and

Figs. 20, 21 and 22 are somewhat diagrammatic views showing the control valves in different positions.

Referring first to Figs. 1, 2 and 3, the embodiment illustrated comprises a platform 25 across which heated metal billets may be discharged in an endwise direction from a suitable furnace (not shown) for delivery into a selected one of three

separate paths or channels 26, 27 and 28 with their entrances arranged in a horizontal row and constituting the receiving guides for a multi-strand rod rolling mill (not shown). Between the platform 25 and the receiving guides there is

provided a switching member or guide device 30 having a pair of upstanding flanges 31 thereon which converge in the direction of travel to form a narrow discharge slot 32. Beneath this slot there is provided a forwardly projecting lug 33 which is adapted to enter one of a series of

notches or recesses 34 underlying and corresponding in number to the channels 26, 27 and 28. To bring the discharge slot 32 into registration with a different channel, the switching member 30 must first be lowered to free the lug 33 from the particular notch 34 within which it happens to be located, whereupon the switching member may be traversed horizontally along the row of entrances to a position adjacent a selected entrance. The switching member will then be raised to bring the slot 32 into registration with the desired entrance, the lug 33 at the same time entering the corresponding notch 34. To allow these movements of the switching member, it is provided with wheels 36 which rest upon a pair of parallel horizontal rails 37 extending in the direction of the desired traversing movement and carried by upstanding arms 38. These arms are secured at their lower ends to horizontal shafts 39 supported in bearings 40. To one of the shafts 39 there is keyed or otherwise secured an operating arm 42 which can be swung back and forth to raise and lower the rails 37 and the switching member 30 resting thereon. As so far described, the apparatus may be similar to that disclosed in the patent to Hawthorne No. 2,181,401 granted November 28, 1939.

In order to raise and lower the switching member 30 in a desired manner, the upper end of the arm 42 is connected by a link 43 to an arm 44 supported in a bearing 45. The upper end of this arm 44 is connected by a link 46 to a crosshead 48 (Fig. 3) which is slidably supported in a stationary guide 49. This crosshead is connected to the piston rod 50 of a fluid motor 51. To obtain the desired traversing movements of the switching member 30, it is connected by a link 53 to a crosshead 54 (Fig. 2) which is slidably supported in a stationary guide 55. This crosshead is connected to the piston rod 56 of a fluid motor 51.

Referring now to Figs. 4, 5 and 6, it will be seen that the fluid motor 51 comprises a double-acting piston 59 secured to the rod 50 and provided with a pair of piston rings 60. This piston is slideable within the cylindrical liner sleeve 61 of a cylinder 62. The ends of the cylinder are closed by plates 63 and 64 having stuffing boxes 65 for the passage of the piston rod therethrough. For convenience the end of the cylinder adjacent the plate 63 will be referred to as the "crank" end and the end adjacent the plate 64 will be referred to as the "head" end. Near the crank end of the cylinder, the sleeve 61 is provided with a circumferential row of ports 67 which communicate with a circumferential groove 68 in the interior of the cylinder 62, this groove communicating with a pipe 69. Similarly, near the head end of the cylinder, the sleeve is provided with a circumferential row of ports 71 which communicate with a circumferential groove 72 in the cylinder, communicating with a pipe 73. The sleeve is also provided with two additional rows of ports 75 and 76 which communicate with grooves 77 and 78 respectively in the cylinder, these grooves communicating with pipes 79 and 80 respectively. The rows of ports 75 and 76 are located between the rows of ports 67 and 71 and adjacent thereto respectively. For convenience the ports 67 and 71 will be referred to as the "outer" ports, and the ports 75 and 76 as the "inner" ports. It will be noted that the inner ports are elongated in the direction of piston travel, and the piston rings 60 are so located and spaced that just before the piston reaches either end of the cylinder they will close the adjacent inner ports. In Fig. 5 the pis-

ton is shown at the head end of its stroke, which corresponds with the raised position of the switching member 30.

The movements of the piston 59 are controlled by a manually operable valve mechanism shown in Figs. 18 to 22 inclusive. This mechanism comprises a pair of three-way cocks or valves 82 and 83, with their rotary plugs aligned and connected by a horizontal shaft 85 to which is keyed or otherwise secured a hub 86 having a handle 87 projecting therefrom. These valves are mounted on a stand 88 which is preferably located at a point from which the operator can conveniently watch the operation of the switching member 30. The port arrangement is the same for both valves and is indicated at the left side of Figs. 20, 21 and 22. A supply pipe 90 delivers a suitable pressure fluid, such as compressed air, to the front opening of the valve 82, and an exhaust pipe 91 is connected to the front of the valve 83. The pipes 69 and 73 are connected respectively to the top and rear openings of the valve 82, and the pipes 79 and 80 are connected respectively to the rear and top openings of the valve 83. With this construction, and the handle 87 lowered as indicated in Fig. 20, the pipes 69 and 80 will be closed, and pressure fluid can flow from the supply pipe 90 through the valve 82, pipe 73 and ports 71 to the head end of the cylinder 62, forcing the piston 59 to the left and lowering the switching member, the fluid escaping from the crank end of the cylinder through the ports 75, pipe 79 and valve 83 to the exhaust pipe 91. As the piston rings 60 gradually close the elongated ports 75, the escaping fluid will be throttled, and the piston will be brought to a smooth stop by the cushioning effect of the fluid trapped in the crank end of the cylinder. Similarly, by raising the handle 87 as shown in Fig. 21, the pipes 73 and 79 will be closed, and pressure fluid can flow from the supply pipe 90 through the valve 82, pipe 69 and ports 67 to the crank end of the cylinder 62, forcing the piston to the right and raising the switching member, the fluid escaping from the head end of the cylinder through the ports 76, pipe 80 and valve 83 to the exhaust pipe 91. Closure of the elongated ports 76 by the piston rings will gradually throttle the escaping fluid and bring the piston to a smooth stop.

Referring now to Figs. 7, 8 and 9, it will be seen that the fluid motor 51 comprises a double-acting piston 93 secured to the rod 56 and slideable within the cylindrical liner sleeve 94 of a cylinder 95. The ends of the cylinder are closed by plates 96 and 97 having stuffing boxes 98 for the passage of the piston rod therethrough. For convenience the end of the cylinder adjacent the plate 96 will be referred to as the "crank" end and the end adjacent the plate 97 will be referred to as the "head" end. Near the crank end of the cylinder, the sleeve 94 is provided with a circumferential row of ports 99 which communicate with a circumferential groove 100 in the interior of the cylinder 95, this groove communicating with a pipe 101. Similarly, near the head end of the cylinder, the sleeve is provided with a circumferential row of ports 102 which communicate with a circumferential groove 103 in the cylinder, communicating with a pipe 104. In addition to the two rows of "outer" ports 99 and 102, the sleeve 94 is provided with three axially spaced rows of "inner" ports 106, 107 and 108 which communicate respectively with annular grooves 110, 111 and 112 in the outer surface of the sleeve, and with pipes 114, 115

and 116 respectively. These inner ports are elongated in the direction of piston travel, their lengths being only slightly less than that of the piston 93. The various parts are so arranged that with the piston closing the row of ports 110, as shown in Fig. 8, the switching member 30 of Fig. 1 will be aligned with the first entrance 26, and when the piston is in position to close the ports 111 or 112 the switching member will be aligned with the entrances 27 or 28 respectively.

The pipes 101 and 104, which lead to the outer ports 99 and 102, are connected with an automatic pilot valve mechanism 118 shown in detail in Figs. 10 to 17 inclusive. This valve mechanism comprises a piston valve 119, preferably H-shaped in longitudinal cross-section, slidably mounted in the cylindrical liner sleeve 120 of a cylinder 121. The ends of the cylinder are closed by plates 122 which carry pins 123 extending axially inward to limit the movements of the valve 119 within the sleeve 120. The sleeve is provided with a pair of diametrically opposed outlet ports 125 leading to a channel 126 in the outer surface of the sleeve, this channel communicating with the pipe 101. The sleeve is also provided with a pair of diametrically opposed outlet ports 127 leading to a channel 128 in the outer surface of the sleeve and communicating with the pipe 104. The ports 125 and 127 are spaced apart axially a distance greater than the length of the valve 119, so that when one set of ports is closed, the other set will be open, and vice versa. In addition the sleeve is provided with a pair of diametrically opposed inlet ports 130 and a second pair of diametrically opposed inlet ports 131, all four of these inlet ports communicating with a channel 132 in the outer surface of the sleeve. This channel 132 is supplied with water or other suitable fluid under pressure by means of a pipe 133 connected to the central portion of the cylinder 121. The inlet ports 130 and 131 are somewhat smaller than the outlet ports 125 and 127, and their remote edges are slightly farther apart than the remote edges of the outlet ports, so that as the valve 119 moves in either direction it will close the outlet ports before the inlet ports are fully closed. It will be noted that adjacent each end of the valve the inlet and outlet ports alternate around the circumference of the sleeve, there being in fact a ninety degree spacing of these ports. A small longitudinal groove 135 extends from one of the inlet ports 130 along the interior of the sleeve to the adjacent end thereof, and a similar groove 136 extends from one of the inlet ports 131 to the other end of the sleeve. These grooves prevent complete closure of the inlet ports, regardless of the valve position.

The three pipes 114, 115 and 116 from the traversing motor of Fig. 8 lead respectively to three stop cocks 138, 139 and 140 (Fig. 18) which in turn are connected to a common drain or discharge pipe 141. The axes of these cocks are aligned horizontally, and each cock has an operating handle 142, the arrangement being such that with the handle raised as shown in Figs. 20 and 21 the cock will be closed, and with the handle lowered as shown in Fig. 22 the cock will be open. The stop cocks are mounted on the stand 88 and beneath the three-way valves 82 and 83. A suitable mechanical interlock is provided to prevent operation of the various handles incorrectly. For this purpose a horizontal shaft 144 is mounted on the stand 88 beneath the shaft 85 to provide a pivoted support for three levers 145, each of which is connected by a link 146 to one of

the stop cock handles 142. Each lever 145 is provided with a projecting lug 147 which is arranged to cooperate with a similar lug 148 projecting from the hub 86. These parts are so constructed and arranged that with all the handles raised, as shown in Fig. 21, the lugs 148 will lie in the path of the lugs 147 and prevent lowering of any of the handles 142. Once the handle 87 has been lowered as shown in Fig. 20, the lugs 148 will be out of the path of the lugs 147, and any of the handles 142 can be lowered. If any one of the handles 142 is now lowered, as shown in Fig. 22, the corresponding lug 147 will lie in the path of the adjacent lug 148 and thereby prevent the handle 87 from being raised until all the handles 142 are in their raised positions.

The operation of the invention will now be apparent from the above disclosure. The handles 87 and 142 will normally be in their raised positions, as shown in Fig. 18, and the switching member 30 of Fig. 1 will be aligned with one of the stock entrances, say the entrance 26 as indicated. Ordinarily there will be bars of stock passing through all of the entrances at the same time, some of these bars being drawn across one of the flanges 31. After a bar has been directed into the entrance 26, the operator will wish to move the switching member 30 into alignment with the entrance which will next be empty for the admission of the next bar. Assume this is the entrance 27. The operator will first lower the handle 87 of the three-way valves 82 and 83, which will admit compressed air from the pipe 90 through the valve 82 and pipe 73 to the right hand end of the elevating motor 51, at the same time allowing the air from the left hand end of the motor to exhaust through the pipe 79, valve 83 and pipe 91. This will move the piston 59 to the left end of the cylinder 62, and this will act through the mechanical connections shown to lower the rails 37 and the switching member 30 carried thereby, freeing the lug 33 from the notch 34. The operator will then lower the handle 142 of the stop cock 139, which corresponds to the selected entrance 27, thereby opening this cock. Water will now flow from the supply pipe 133 through the channel 132 (Figs. 10 and 11) and inlet ports 131 into the sleeve 120, thence through the outlet ports 127, channel 128, pipe 104 and ports 102 to the right hand end of the cylinder 95 (Fig. 8), and thence through the ports 101, pipe 115 and cock 139 to the discharge pipe 141. Since the inlet ports 131 restrict the water flow, and particularly since these ports are smaller than the outlet ports 127, there will be a decided reduction in the water pressure on the right hand side of the valve 110, and as a result the higher water pressure on the other side of the valve will force it to the right until the outlet ports 127 are closed and the inlet ports 131 are nearly closed. This will fully open the inlet ports 130 and the outlet ports 125, allowing the water from the pipe 133 to flow through the pipe 101 and ports 99 into the left end of the cylinder 95. The water pressure will move the piston 93 to the right, the water on the right side of the piston exhausting through the pipe 115, until the piston reaches a position to close the ports 101. This will prevent further exhausting of the water. The water pressures on the two sides of the piston will balance, and it will come to rest, having moved the lowered switching member 30 of Fig. 1 along the rails 37 and into position adjacent the entrance 27. The operator will then close the stop cock 139 by raising

its handle 142, and then raise the handle 87 of the three-way cocks 82 and 83. This will admit compressed air through the pipe 69 to the left end of the elevating motor 51, while exhausting air from the right end thereof through the pipe 80, and the piston 59 will move to the right, raising the rails 37 and the switching member 30 to bring the slot 32 into registration with the entrance 27, the lug 33 at the same time entering the corresponding notch 34. Merely by manipulation of the handle 87 and a selected handle 142, the operator can cause the switching member to move to any selected entrance, regardless of the position which it may happen to occupy. If this movement requires a reversal of its previous traversing movement, the pilot valve piston 119 will be reversed automatically by the fluid pressure, whereas if two successive movements of the switching member are in the same direction, no reversal of the pilot valve will occur. In moving the switching member to the intermediate entrance 27, the piston 93 may approach the ports 107 from either the right or the left side, but it will come to rest accurately in the same position in each case, since the piston is only slightly longer than the ports in order to ensure complete closure thereof. It will be understood that if more than three entrances are to be served by the switching member, additional rows of inner ports will be provided for the traversing cylinder, each row of course having its individual exhaust pipe connection and stop cock. This will not affect the operation in any respect.

The invention is comparatively simple and inexpensive. It eliminates a large part of the mechanism required by the previously patented Hawthorne construction, and enables a single traversing motor to be used regardless of the number of entrances to be served. The operation is smooth, accurate and dependable. Both the motors are of the double-acting type, and therefore ensure positive movements of the switching member in all required directions.

Having thus described our invention, what we claim as new and desire to secure by Letters Patent is:

1. Actuating mechanism for a switching member which is movable into registration selectively with each of a row of more than two stock-receiving channels comprising a double-acting fluid motor to move the member to and from a path offset from the said row, manually controlled valve mechanism to control the motor, a second double-acting fluid motor having a movable element to move the member along the said path, a second manually controlled valve mechanism to cause the element to move into predetermined positions corresponding to the said channels, and a mechanical interlock preventing operation of the second valve mechanism until the first valve mechanism has been operated to move the switching member to the offset path.

2. Actuating mechanism for a switching member which is movable selectively into each of a series of more than two positions comprising a cylinder, a double-acting piston slideable therein and adapted to be connected with the said member, the cylinder having two outer ports adjacent its opposite ends and a series of axially spaced inner ports intermediate the outer ports, the piston being arranged to close the respective inner ports when moved into predetermined positions corresponding to the said positions of the switching member, manually controlled valve mechanism to control the discharge of fluid from the cylinder through the inner ports, a valve casting having a cylindrical bore with two axially spaced outlet ports opening laterally into the bore, means connecting the outlet ports respectively with the said outer ports, a cylindrical pilot valve slideable in the bore to control the outlet ports by sliding over one or the other thereof, and means to supply fluid under pressure to the bore on both sides of the valve regardless of the valve position, the pilot valve moving automatically by fluid pressure differential to close such of the outlet ports as is connected to an outer port in communication through the cylinder with an inner port which is discharging fluid.

3. Actuating mechanism for a switching member which is movable selectively into each of a series of more than two positions comprising a cylinder, a double-acting piston slideable therein and adapted to be connected with the said member, the cylinder having two outer ports adjacent its opposite ends and a series of axially spaced inner ports intermediate the outer ports, the piston being arranged to close the respective inner ports when moved into predetermined positions corresponding to the said positions of the switching member, manually controlled valve mechanism to control the discharge of fluid from the cylinder through the inner ports, a valve casting having a cylindrical bore with two axially spaced outlet ports opening laterally into the bore, means connecting the outlet ports respectively with the said outer ports, a cylindrical pilot valve slideable in the bore to control the outlet ports by sliding over one or the other thereof, the valve casting having two axially spaced inlet ports communicating with the bore on opposite sides of the valve and somewhat smaller than the outlet ports, and means to supply fluid under pressure to the inlet ports, the pilot valve moving automatically by fluid pressure differential to close such of the outlet ports as is connected to an outer port in communication through the cylinder with an inner port which is discharging fluid.

CHARLES W. HAWTHORNE.
GEORGE P. MALM.
